[57] CLAIM

The ornamental design for a scarf holder, as shown and described.

DESCRIPTION

FIG. 1 is a perspective view of the scarf holder shown on a scarf;

FIG. 2 is a front elevation view of the scarf holder; and,

FIG. 3 is a rear elevation view of the scarf holder.

The broken line showing of a wearer and scarf in FIG. 1 is for illustrative purposes only and forms no part of the claimed design.
